Primary Examiner — Mark A Goodwin*Assistant Examiner* — Benjamin M Weeks(74) *Attorney, Agent, or Firm* — Michael Petrin; Peter Tormey; Antero, Tormey & Petrin, PC(57) **CLAIM**

We claim the ornamental design for a linear catadioptric lens assembly, as shown and described.

DESCRIPTION

FIG. 1 is a top perspective view of an embodiment of a linear catadioptric lens assembly, showing the new design;

FIG. 2 is a left side view thereof;

FIG. 3 is a right side view thereof;

FIG. 4 is a top view thereof;

FIG. 5 is a bottom view thereof;

FIG. 6 is a back view thereof; and,

FIG. 7 is a front view thereof.

The broken line showing of a bracket is meant to indicate indeterminate length. The bracket and the space in between the bracket from no part of the claimed design.
